UNITED STATES PATENT OFFICE.

GUSTAF H. EKSTROM, OF Rockford, Illinois, ASSIGNOR TO C. PAUL PARKER,
TRUSTEE, OF EVANSTON, ILLINOIS.

RUBBING MACHINE.

Application filed June 11, 1923. Serial No. 644,565.

The invention relates to improvements in rubbing and polishing machines having reciprocatory rubbing elements, and particularly to the attachment and construction of the pad holders for such machines.

Machines of the above type are commonly constructed with elongated rubbing pads arranged to reciprocate side by side, or with pads arranged to reciprocate toward and from each other. In both instances each pad holder is usually rigidly connected to a downwardly displaced attaching portion of a bearing slide or other reciprocating member and is therefore poorly adapted for work on curved surfaces. This is particularly true of pad holders which are arranged to reciprocate toward and from each other.

The primary object of the invention is to provide a rubbing machine having pivotal pad holders which is well adapted for work on curved surfaces.

A further object is to provide a rubbing machine having pad holders arranged to reciprocate toward and from each other, which is adapted for work on curved surfaces.

Another object is to provide a rubbing machine in which a plurality of pad holders are pivotally mounted to each bearing slide at opposite ends of the machine.

Further objects and advantages will become apparent as the description proceeds.

In the drawings, wherein I have illustrated the preferred embodiment of my invention, Figure 1 is a side elevation of the rubbing machine. Fig. 2 is an end elevation. Fig. 3 is a perspective view on a large scale of a bearing slide forming part of the machine.

Referring to the drawings, 10 indicates the body of a rubbing machine of well known construction which houses the bearing slides 11 adapted to be reciprocated therein.

Each bearing slide 11 is formed with a downwardly displaced attaching portion 12 at one end. Downwardly extending projections 13 having longitudinal bores 14 therethrough are formed at opposite sides of the portions 12. Pad holders 15 supporting rubbing pads 16 and having upstanding lugs 17 overlapping with the projections 13 are pivotally secured to the latter by pins 18. The lower ends of the projections 13 are rounded, and the pad holders which are

arranged side by side are sufficiently spaced from each other to allow a free pivotal movement about the pins 18.

By providing pivotal pad holders, a rubbing machine is obtained which is particularly adapted for work on curved surfaces. By attaching pad holders to the rounded projections 13 at opposite sides of the bearing plates which are arranged to reciprocate toward and from each other, a machine adapted for work on curved surfaces is obtained which is also free from an objectionable amount of vibration and side wobble.

It is to be noted especially that there are a plurality of pad holders secured to the reciprocatory means on two spaced fixed axes constrained to extend at all times in the direction of reciprocation. The pad holders are in the present instance adapted to form a trough. By this construction pad holders on the separate axes can be made to assume an angular relation to each other, which adapts them for reciprocation along the elements of a curved surface, such as a cylinder, for example. It is further to be noted that the angularity produced by the pivotal relations described is important only as between the pad holders and not particularly so as between each pad holder and the reciprocating means. In the present instance, two pads on one side are arranged to lie in the same plane and the other two pad holders, laterally offset relative to the first, are pivoted on alined axes so that both end sets together form alined troughs.

While I have herein disclosed the preferred embodiment of my invention with considerable particularity for purposes of illustration, various changes may be made without departing from the spirit and scope of the invention as expressed in the appended claims.

I claim as my invention:

1. In a rubbing machine, in combination, a reciprocatory slide, a pad holder secured to said slide, and a second pad holder adjacent the first and pivotally secured to the slide about a fixed axis constrained to extend at all times in the direction of reciprocation.

2. A rubbing machine having, in combination, a bearing slide, a downwardly displaced attaching portion on said slide, parallel downwardly extending projections on said portion, and two pad holders pivotally

secured to said projections, said pad holders being mounted in parallel closely spaced relation on fixed pivotal axes extending in the direction of reciprocation.

5 3. A rubbing machine having, in combination, two members arranged to reciprocate in the same general direction, two pad holders on each member, two of the holders

on separate members being pivoted on fixed and alined axes extending in the direction of reciprocation, and the other two being arranged to lie in the same plane parallel to the alined axes. ¹⁰

In testimony whereof, I have hereunto affixed my signature.

GUSTAF H. EKSTROM.
